YIELDABLE BELT BUCKLE

Ludwig A. Stark, Tenafly, N. J.

Application June 28, 1951, Serial No. 234,021

2 Claims. (Cl. 24—178)

1

This invention relates to new and useful improvements in yieldable belt buckles.

Yieldable belt buckles may be classified in two distinct classes, namely, those in which the frame of the buckle is made from two or more sections resiliently connected together, and those in which the frame is of one piece but is connected at one side by resilient means with a leather or other flexible belt. This invention is directed to the second group of yieldable belt buckles. In this group it is customary to connect the resilient means to the leather or other material belt with rivets, tabs, and other direct attachments. The main defect of this type of construction resides in the fact that the rivets, tabs or other direct attachments tend to place a great strain on the material of the belt at the point or points of attachment so that in a short time the connection becomes worn and loose or broken. The dominating object of this invention resides in so connecting the resilient means to the belt that there is no actual direct attachment between these parts. It is proposed, instead, that the connection be in the nature of a clamping action or an "under pressure" action.

Another important object of this invention resides in so arranging the resilient connection that the "under pressure" action is directed against the inside of the bend of a belt having an inwardly bent end portion adjacent the belt buckle. The pressure is distributed across the entire length of this bent portion so as to distribute strain, and in this way increase the life of the connection and thus of the belt.

It is proposed to characterize the new yieldable belt buckle by the fact that it includes a casing having a rounded end portion for engaging inside of said bend of the belt. It is proposed to provide this rounded end portion with a stem guiding opening. A stem is slidably engaged through said stem guiding opening and has its outer end formed with coiled portions for engaging around and holding one end of the belt buckle frame. It is proposed to provide resilient means urging said stem inwards of said casing and urging said coiled portions towards and against said rounded end portions of the casing in order to clamp the attachment of the belt buckle upon the bend of the belt. The bend of the belt will be clamped in between the rounded end portion of the casing and the coiled portions of the stem when the yieldable belt buckle is in its relaxed condition. When in action, and the stem is drawn outwards, the rounded end portion of the casing will be "under pressure" against the bend of the belt.

2

In many prior yieldable belt buckles tension springs were used to provide the resiliency for expansion. This invention particularly proposes to use a compression spring which experience has proved can stand up better for this particular job. With a tension spring the entire strain is communicated to the end turns or hooks or hinges by which it is attached and there is the tendency for the spring to lose some of its resiliency at these points after some use, particularly if it is stretched often or over stretched. This injury is not possible with a compression spring since all of the coils will merely move towards or against each other and prevent injury to the spring when the load is applied which is distributed equally to all turns.

In prior yieldable belt buckle constructions the spring would lean against the adjacent walls of the belt, of leather or other high friction material, during expansion and contraction thereof. This contact is objectionable because of the large coefficient of friction between a stretching spring and a leather or other belt. This invention proposes to so construct the casing of the yieldable belt buckle that it encases the spring in order that the spring leans against the casing, of metal or other material having a low coefficient of friction during stretching and contraction. The friction with this construction is naturally smaller than in the prior explained case.

30 Another object of the invention is the construction of a device as described which is simple and durable and which may be manufactured and sold at a reasonable cost.

35 For further comprehension of the invention, and of the objects and advantages thereof, reference will be had to the following description and accompanying drawing, and to the appended claims in which the various novel features of the invention are more particularly set forth.

40 In the accompanying drawing forming a material part of this disclosure:

Fig. 1 is a fragmentary plan view of one end of a belt provided with a yieldable belt buckle constructed in accordance with this invention.

45 Fig. 2 is a sectional view taken on the line 2—2 of Fig. 1.

Fig. 3 is an enlarged transverse sectional view taken on the line 3—3 of Fig. 2.

50 Fig. 4 is a fragmentary horizontal sectional view taken on the line 4—4 of Fig. 2, but illustrated with the yieldable belt buckle expanded.

Fig. 5 is a perspective view of the casing used in the yieldable belt buckle.

55 Fig. 6 is an end elevational view of the casing shown in Fig. 5, looking from the right hand end.

The yieldable belt buckle, in accordance with this invention, includes a belt buckle frame 10 having a buckle tongue 11 pivotally mounted on one end 12 of said buckle frame 10. A casing 13 having a rounded end portion 14 engages inside of the bend 15 of a belt 16 having an inwardly bent end portion 17 attached to the adjacent portion of said belt 16 with a transverse line of stitches 18 extended along the end of the bent end portion 17, and longitudinal lines of stitches 19 extended along the sides of the inwardly bent end portion 17.

The rounded end portion 14 of the casing 13 is formed with a stem guiding opening 20. The bend 15 is formed with an opening 31 aligned with said opening 20. As stem 21 is slidably engaged through said opening 31 and said stem guiding opening 20. The outer end of said stem 21 is formed with end coils 22 engaging around and holding said end 12 of said belt buckle frame 10. Resilient means in the nature of a compression spring 23 is associated with said stem 21 and casing 13, for urging said stem 21 inwards and urging said coil portions 22 towards the rounded end portion 14 of the casing 13. The casing 13 is formed from a strip of metal bent at its center to form the rounded end portion 14. The casing 13 has top and bottom portion 24 and 25, respectively extending over and under said spring 23 and stem 21. These top and bottom portions 24 and 25 are provided with side flanges 26 directed towards each other to facilitate encasing said spring 23 and stem 21. The top and bottom portions 24 and 25 are narrower than said rounded end portion 14 which preferably extends substantially the entire width of the belt 16. The inner end of the stem 21 is formed with a split 27, and the parts 28 to the sides of this split 27 are spread outwards so as to hold the adjacent end of the spring 23 connected with the stem 21. The coil portions 22 are slightly spaced from each other providing an opening 29 through which the buckle tongue 11 extends. The outer end of the stem 21 is formed with a widened part 30 from which the coil portions 22 are formed. This widened part 30 is adapted to engage against the outside of the bend 15 of the belt 16, see particularly Fig. 1. The stem 21 is of rectangular shape in cross section. The spring 23 is wound around the stem 21 (see Fig. 3).

The operation and use of the new yieldable belt buckle may be understood from the following:

Figs. 1 and 2 illustrate the belt buckle in its released condition. In this condition the expansion spring 23 is forcing the widened portion 30 of the stem 21 against the outside of the bend 15 and simultaneously is forcing the rounded end portion 14 of the casing 13 against the inside of the bend 15 of the belt 16. This clamping action serves to securely connect the yieldable belt buckle with the belt 16. In action, the belt buckle frame 10 is pulled outwards, which in turn pulls the stem 21 outwards, as illustrated in Fig. 4. The spring 23 is compressed and the rounded end portion 14 of the casing 13 is engaged under pressure against the inside of the bend 15. It

should be particularly noted that with this construction there are no strains or stresses between rivets or tabs or other direct attachments to the belt 16. When the pressure is released the spring 23 will move the stem 21 and belt buckle frame 10 back to their original positions.

The yieldable belt buckle is attached to the belt 16 in the following way. Originally, the inner end of the stem 21 does not contain the split 27 or the outwardly bent parts 28. The casing 13 is engaged against the bend 15 of the belt 16, and then the stem 21 is inserted through the openings 31 and 20 of the bend 15 and rounded end 14, respectively. The spring 23 is then placed on the stem 21 within the top and bottom portions 24 and 25 of the casing 13. Now the inner end of the stem 21 is formed with said split 27 and the parts 28 are spread open to hold the spring 23 in position. The end portion 17 of the belt 16 is now secured to the belt 16 with the stitches 18 and 19.

While I have illustrated and described the preferred embodiment of my invention, it is to be understood that I do not limit myself to the precise construction herein disclosed and the right is reserved to all changes coming within the scope of the invention as defined in the appended claims.

Having thus described my invention, what I claim as new and desire to secure by United States Letters Patent is:

1. In a yieldable belt buckle, a metal casing having a rounded end portion for engaging inside of the bend of a belt having an inwardly bent end portion attached to the adjacent portion of said belt, said rounded end portion having a stem guiding opening, a stem slidably engaging through said stem guiding opening and having at its outer end coil portions for engaging around and holding one end of a buckle frame having a buckle tongue mounted on said one end of said buckle frame, a compression spring mounted around said stem and located within said casing and having one end abutting said rounded end portion, and having its other end connected with said stem, and said casing having flat, rigid, parallel top and bottom portions extending over and under said spring and said stem for shielding said spring from direct contact with said belt.

2. A yieldable belt buckle as defined in claim 1, in which said top and bottom portions have side flanges directed towards each other for facilitating encasing said spring and stem.
